UNITED STATES PATENT OFFICE.

HANS M. BOE, OF MINNEAPOLIS, MINNESOTA.

PUMP-PLUNGER.

1,351,328.

Specification of Letters Patent. Patented Aug. 31, 1919.

Application filed November 22, 1919. Serial No. 339,808.

To all whom it may concern:

Be it known that I, HANS M. BOE, a citizen of the United States, resident of Minneapolis, county of Hennepin, State of Minnesota, have invented certain new and useful Improvements in Pump-Plungers, of which the following is a specification.

The object of my invention is to provide a plunger of such construction that leakage between the wall of the pump barrel and the plunger will be reduced to a minimum.

A further object is to provide a plunger of simple construction and one which will be inexpensive to maintain and be strong and durable.

The invention consists generally in various constructions and combinations, all as hereinafter described and particularly pointed out in the claims.

In the accompanying drawings forming part of this specification,

Figure 1 is a vertical sectional view through a pump and plunger embodying my invention, showing it adapted for connection with a grease container.

Fig. 2 is a sectional view through a portion of the plunger.

Fig. 3 is a top view of the plunger.

In the drawing, 2 represents a tank or container having a leg 3 and caster supports 4 upon which the tank is moved conveniently from place to place. At the bottom of the tank is an outlet or discharge port leading to a passage 9 which terminates in an elbow 10 into which a nipple 11 is tapped. 12 represents a pump head connected with the upper end of the nipple and containing a chamber 13 the nipple having a seat 14 for a ball valve 15 which normally rests by gravity upon the seat and closes the passage to the nipple. A pump barrel 15' is seated on the top of the pump head 12 and communicates therewith through a passage 16, a pin 17 being mounted in the walls of said head and bridging said passage to prevent the valve 15 from being drawn into the barrel on the upstroke of the plunger. A pin 17' is also provided in the wall of the head 12 to limit the movement of the ball valve 15 toward the discharge port of the head. A piston rod 18 is mounted in said barrel and has a head 19 at its lower end that is tapped to receive a bolt 20 and piston cups 21 are placed back to back on said bolt and seated against said head, being

clamped securely thereon by the tightening of said bolt. These cups are preferably of leather or some other suitable flexible material and their edges are held in contact with the inner walls of the barrel, preferably by means of metallic disks 22. These disks I prefer to make of thin sheet brass, pressed or spun to a suitable shape, and having a series of radial slits 23 in their edges to form a series of spring-like tongues 24 which, when the edge of the disk is folded to fit the flexible cup of the piston, lap one another slightly on one side, as indicated in Fig. 3 and have the function of holding the flexible edges of the cups against the walls of the barrel with a yielding pressure.

In making these disks I prefer to use thin sheet brass and cut a series of radial slits in the edges thereof and when the disk is folded to the form shown in Fig. 2, the abutting edges will slide by each other, said edges being slightly offset in the act of cutting the slits, so that it is only necessary to fold the disk to the form shown in Fig. 2 when the tongues 24 will assume the position illustrated in Fig. 3, each tongue pressing the other and all of them exerting an outward spring-like pressure to hold the edges of the cups in yielding contact with the walls of the pump barrel. The pump rod has a rack 25 thereon engaging the teeth of a pinion 26 mounted on a shaft 27 and above the barrel is a pipe 28 having its upper end mounted in the top of the tank and forming a guide for the reciprocating piston rod. The pump head 12 also has a gravity valve 29 normally closing the port leading to the hose 30 through which the lubricating material is discharged by the action of the plunger. This hose has a suitable nozzle 31 and a valve 32.

I claim as my invention:

1. A pump plunger comprising a rod, piston cups of flexible material placed back to back and having means for securing them to the end of said rod, metallic disks fitting within said cups and having a series of radial slits in their peripheral edges, a series of spring tongues being formed by said slits, the edges of abutting tongueslapping by each other and said tongues exerting an outward spring-like pressure on the edges of said piston cups.

2. A piston comprising a flexible cup, a metallic disk fitting therein and having a series of peripheral radial slits forming a

series of tongues which, when said disk is folded to fit the cup, lap each other and exert a yielding pressure on the walls of the cup.

10

- 5 3. A piston comprising a flexible cup, a disk fitting therein and having a series of peripheral radial slits forming a series of

tongues which, when said disk is folded to fit the cup, lap each other and exert a yielding pressure on the walls of the cup.

In witness whereof, I have hereunto set my hand this 17th day of November 1919.

HANS M. BOE.
